UNITED STATES PATENT OFFICE.

ARNO SCHMIDT, OF HAYWARD, CALIFORNIA.

CAN-FILLING MACHINE.

1,420,222.

Specification of Letters Patent. Patented June 20, 1922.

Application filed February 17, 1919. Serial No. 277,398.

To all whom it may concern:

Be it known that I, ARNO SCHMIDT, a citizen of Germany (who has taken out his first papers as a citizen of the United States), 5 residing at Hayward, in the county of Alameda, State of California, have invented a new and useful Can-Filling Machine, of which the following is a specification in such full and clear terms as will enable those 10 skilled in the art to construct and use the same.

This invention relates to a machine for filling cans and its object is to produce a machine which will be capable of continuously filling cans as they pass through the machine and without stopping them during such movement.

Another object of the invention is to provide means whereby a measured quantity 20 of the product may be placed into the tins and whereby such quantity may be varied as may be necessary for different sized receptacles.

Another object of the invention is to provide a moving stream of the material being handled without the use of a movable nozzle.

Other objects of the invention will appear as the description proceeds.

An embodiment of the invention is shown 30 in the drawings in which the same reference numeral is applied to the same portion throughout, but I am aware that there may be modifications thereof.

Figure 1 is a side elevation partly in section of the complete machine,

Figure 2 is a view in elevation looking in the opposite direction from Figure 1,

Figure 3 is an end elevation of the complete machine,

Figure 4 is a plan view of the complete machine,

Figure 5 is a side elevation in section of a modified form of the feeding device in which two cans at a time are moved into 45 position,

Figure 6 is a view partly in section of a still further modified form of feeder in which three cans are receiving material at one time.

The machine comprises a bed plate 1 having suitable legs 2, 3, 4, and 5. The bed supports a horizontal driving shaft 6 and two vertical shafts 7 and 8. The two vertical shafts 7 and 8 are provided with sprocket 50 wheels 9 and 10 which wheels in turn carry

a sprocket chain 11 which chain has suitable flights 12 thereon to properly space the cans as they pass through the machine. The shaft 8 is also provided with a hub 13 carrying three arms 14, 15, and 16 which position 60 the cans with respect to the chain properly as they are placed upon the bed 1.

Near the center of the bed there is a flat post 17 which is provided with vertical slots 18, 19 and 20. The two slots 18 and 20 have 65 cap screws 21 and 22 extending therethrough into the hopper frame 23. The hopper frame has a lug 24 which extends into the slot 19, which lug is for the purpose of adjusting the height of the hopper, a screw 25 being 70 used for this purpose. The screw 25 extends through the lug 24 and it is operated by means of a hand wheel 26 at its lower end.

Above the hopper frame there is the hopper 75 27 which terminates in a cylindrical shell 28 just in front of the hopper frame. This cylindrical shell is slotted at 29 and 30, the former slot being for the purpose of allowing material to pass into the measuring apparatus, and the latter for the purpose of 80 discharging it therefrom.

Within the shell 28 there is another shell 32 which is provided with a pair of spiral slots 33 and 34, and which is divided into two compartments by means of the partition 85 35. This shell has a cross bar 36 at each end, which cross bars are secured in place in the shell in any suitable manner and it has set screws 37 extending therethrough, which screws have heads extending between 90 two pair of lugs 38 and 39 on slideable heads 40, the object being to adjust the sizes of the two chambers in the shell 32 as may be required for the given size receptacle to be filled.

The hopper frame has an arm 42 rigidly connected therewith which extends to and surrounds the vertical shaft 7. This arm also provides a bearing for a shaft 43 carrying a bevel gear 44 and a spur gear 45, the latter in mesh with the ring gear 46 carried by one end of the measuring shell 32.

The shaft 7 has a feather way and drives a bevel gear 47 which is in mesh with the bevel gear 44; and as the hopper frame is 105 raised or lowered the bevel gear 47 is raised or lowered.

The apparatus is driven from a pulley 48 on the horizontal shaft 6. The ratio of the gears is such that the cans will be moved 110

into position under the spiral slots of the shell 32 just as said slots begin to discharge the material within the shell through the slot 30, and the cans will move along under said slots as the material is discharged therefrom until all of the material has been discharged therefrom at the opposite end of the slot 30.

In practice the hopper is filled with the material to be placed in the cans and as the 10 compartments of the shell 32 are filled when the slots are on the upper side of the shell the material will be discharged therefrom through the slot 30 into the cans when said shell turns to the opposite position and said 15 cans will always be maintained under the main stream of material by the flights of the sprocket chain. The table 1 is slotted as indicated at 49 and the legs of the machine also support a shelf 50 upon which a suitable 20 bucket 51 may be placed to collect whatever of the material may fall through the table 1 when it may happen that a can has not been placed in the proper position to be filled.

In the form of the invention shown in 25 Figure 5 the outside shell is indicated at 60, the slots therein at 61 and 62, and the cans are arranged to be placed at 63 and 64 in such order as to be receiving material from two streams passing out of the slots 65 and 30 66 of the revoluble shell 67.

In the form of the invention shown in Figure 6 the outer shell 70 has the inlet slot 71 and outlet slot 72; while the revoluble shell 73 has a single continuous spiral slot 35 74, the pitch of which is so arranged that three cans 75, 76, and 77 will be filling at one time.

Having thus described my invention, what I claim as new and desire to secure by Letters Patent of the United States is as follows, express reservation being made of permissible modifications.

1. A can filling machine comprising a hopper having an elongated slot, means to advance a series of cans longitudinally of said slot below the same, a slotted cylinder revoluble in contact with said hopper the slot in said cylinder being formed to deliver a restricted stream of material from the hopper 40 slot progressively along the same and into the cans as they pass thereunder.

2. A can filling machine comprising a table, means to advance a series of cans thereover, a feed hopper having an elongated slot 45 in its bottom under which the cans pass, a spirally slotted cylinder revoluble in contact with the feeding hopper whereby a restricted stream of material will be delivered from

said elongated slot progressively along the same as the cans pass thereunder. 60

3. A can filling machine comprising a table, a feeding hopper thereover having an elongated slot in its bottom, a slotted feeding member revoluble in contact with the bottom of the hopper the cylinder slot being formed to discharge a movable stream of material from the hopper slot and means to advance a series of cans under said slot in the same position and at the same rate as the stream is movable along the same. 70

4. A can filling machine comprising a table, means to move a series of cans along the table, a feeding hopper having an elongated slot under which the cans move, means to adjust the feeding hopper vertically, a spirally slotted cylinder revoluble in contact with the bottom of the hopper for delivering a restricted stream of material progressively from the slot in said feed hopper into the several cans as they travel under said 75 hopper.

5. A can filling machine comprising a table, means to move a series of cans along the table in succession, a slotted feed hopper under which the cans pass, means to adjust 80 the feed hopper vertically and a separate movable member in the bottom of the feed hopper having a slot inclined to the hopper slot to deliver a measured stream of material into the cans as they successively pass 85 under the feed hopper.

6. A can filling machine comprising the combination of a table of means to move a series of cans along the same in succession, a feed hopper having an elongated slot in its 90 bottom, a revoluble double chambered cylinder in said hopper having a pair of spirally arranged slots, and means to rotate said cylinder so that the spiral slots cross the elongated slot immediately over the cans as they 95 move under said elongated slot.

7. A can filling machine comprising a table, a conveyer to move a series of cans along the table in succession, a slotted feed hopper under which the cans move, a cylinder revoluble in the feed hopper and having two chambers with two spirally arranged slots, means to rotate said cylinder to deliver a stream of material into each can as it passes 100 under the feed hopper and means to adjust the size of the compartments in said cylinder. 105

In testimony whereof I have hereunto set my hand this 31st day of January, A. D. 110 1919.

ARNO SCHMIDT.
